CALEB E. SUMMERS, OF PONTIAC, MICHIGAN, ASSIGNOR TO GENERAL MOTORS CORPORATION, OF DETROIT, MICHIGAN, A CORPORATION OF DELAWARE

INTAKE MANIFOLD

Application filed May 8, 1930. Serial No. 450,700.

The principal object of this invention is to provide, in the induction system of a multi-cylinder internal combustion engine which includes a charge forming device and a manifold, in which there are provided a main passage leading from the charge forming device, a branch passage leading from the main passage to a cylinder or cylinders, and a second branch passage leading from the main passage to a cylinder or cylinders whose suction strokes alternate symmetrically with the suction strokes of the cylinder or cylinders to which the first branch leads, means to insure that uniform and properly measured quantities of combustible mixture will be supplied to the two branch passages when the engine is operating with the throttle valve closed or only slightly opened.

Broadly speaking, the invention resides in providing in the induction system of an engine of the type described above, a by-passage which communicates at one end with the main passage on the atmospheric side of the throttle valve and communicates at its opposite end with two passages of which each communicates with one of the branch passages of the manifold.

For a better understanding of the nature and the objects of the present invention, reference is made to the following specification in which there is described the preferred embodiment of my invention which is illustrated in the accompanying drawings.

In the accompanying drawings:

Figure 1 is a top plan view of an internal combustion engine of the V-type, with parts of the charge forming device broken away.

Figure 2 is an enlarged section through the intake and exhaust manifolds taken substantially on the line 2-2 of Figure 1.

Figure 3 is a top plan view of the intake and exhaust manifold headers, with the throttle valve removed.

Figure 4 is a section taken on substantially the line 4-4 of Figure 3.

In the drawings, the reference character 10 indicates an internal combustion engine of the V-type which includes two cylinder blocks 11 and 12 in each of which there are provided

50 four cylinders. In each of the cylinders, there

is provided a piston which is connected by means of a connecting rod to one of the crankpins of a crankshaft which is journalled in suitable bearings in the crankcase. The throws of the crankshaft are so arranged 55 that the explosions in the cylinders (which are indicated by the reference characters *a*, *b*, *c*, *d*, *e*, *f*, *g* and *h*, respectively) and, consequently, the suction strokes of the pistons, 60 occur in the order *a*, *f*, *c*, *e*, *d*, *g*, *b*, *h*.

The intake manifold includes a conduit 13 which communicates at its front end with the cylinders *a* and *b* and at its rear end with the cylinders *c* and *d* and a conduit 14 which communicates at its front end with the cylinders *e* and *f* and at its rear end with the cylinders *g* and *h*.

The exhaust manifold includes a conduit 15 which communicates with the cylinders in the block 12 and a conduit 16 which communicates with the cylinders in the block 11 and through an intermediate portion of whose lower wall there extends an opening 17 through which the exhaust gases may pass into an exhaust pipe and, thence, to the atmosphere.

Between the cylinder blocks 11 and 12, there is located a header 18 in which there are provided an intake passage 19, whose opposite ends communicate with the conduits 13 and 14, respectively, and below the intake passage an exhaust passage 20 whose opposite ends communicate with the conduits 16 and 15, respectively, and through which the exhaust gases from the cylinders in the block 12 may pass from the conduit 15 into the intermediate portion of the conduit 16 and, thence, through the opening 17 and the exhaust pipe to the atmosphere.

Into the upper side of the intake header, there extends an opening which is surrounded by an upwardly extending neck 21 to which the charge forming device 22 is adapted to be connected, as shown in the drawings. Within the upper end of the neck, there is located a butterfly type throttle valve 23 which is secured to a shaft 24 which is journalled in the wall of the neck and to which is secured an operating arm.

Extending at a right angle to the axis of

the intake passage 19 and diametrically with respect to the neck 21, there is located a partition 25 which subdivides the interior of the intake passage and the neck. The upper edge 5 of the partition 25 is formed as the arc of a circle whose center is located in the axis of the shaft 24 and whose diameter is just sufficiently greater than the diameter of the throttle valve 23 to insure that the wall will 10 not interfere with operation of the throttle valve.

When the engine is operating, the partition 25 serves to divide the stream of combustible mixture which passes the throttle valve into 15 two streams of which one flows into each of the branches of the passage 19 whence it passes into the adjacent conduit (13 or 14) and, thence, into the cylinders of the engine which communicate with that conduit. When 20 the engine is operating with the throttle valve opened considerably, the volume of combustible mixture which passes the throttle valve on one side of the plane passing through the partition 25, will be substantially equal 25 to that which passes the throttle valve on the other side of the plane and, consequently, the volume of combustible mixture which passes into one branch of the passage 19 will be substantially equal to that which passes into 30 the other branch thereof. However, since it is not commercially practicable to manufacture throttle valves so that they fit the passages which they are designed to control uniformly throughout their circumferences, 35 when the engine is operating with the throttle valve closed or only slightly opened, the volume of combustible mixture which passes the throttle valve on one side of the plane which passes through the partition 25 is like- 40 ly to be greater or less than that which passes the throttle valve on the other side of the plane and, consequently, it is likely that, under these conditions, non-uniform and unequal volumes of combustible mixture will 45 be supplied to the two branches of the conduit 19 and to the cylinders in the blocks 11 and 12. To eliminate the possibility of such faulty distribution of the combustible mixture occurring when the engine is operating 50 with the throttle valve closed or only slightly opened, I have provided means for bypassing the greater part of the combustible mixture around the throttle valve under these conditions. This means includes a vertical bore 26 which extends through a wall of the neck 21 and communicates at its upper end 55 with a transverse bore 27 which opens into the interior of the neck on the atmospheric side of the throttle valve 23. The lower end of 60 the bore 26 communicates with a transverse bore 28 which extends into the partition 25 and terminates substantially at the center of the neck 21. Into the inner end of the bore 28, there extends through the partition 65 25 from each side thereof, a bore 29 which

is so inclined as to direct the combustible mixture discharged therefrom into the conduit (13 or 14) which communicates with the branch of the passage 19 into which it opens.

When the engine is operating with the throttle valve closed or only slightly opened, the suction created by the pistons on their suction strokes will draw the greater proportion of the combustible mixture generated by the charge forming device into the bore 26 whence it will pass, successively, into the bores 27 and 28. From the bore 28, combustible mixture will be discharged through the bores 29 alternately into each branch of passage 19 and will, together with combustible mixture which has entered the passage 19 from the neck 21, pass into the cylinders in the adjacent block (11 or 12). On account of the great difference in the pressures existing at the opposite ends of the by-pass, when the engine is operating with the throttle valve closed or only slightly opened, and the size of the bores 29, the fuel in the combustible mixture which is drawn into the by-pass will be discharged from the bores 29 in an atomized condition and at such high velocity that it will be carried to the cylinders without being condensed. Since the engine suction will be applied alternately to each of the bores 29 and since the suction applied to one of the bores 29 will be substantially equal to that which is applied to the other bore 29, equal quantities of combustible mixture will alternately be discharged into each of the branches of the passage 19 and non-uniform and unequal distribution of combustible mixture will, consequently, be eliminated.

To regulate the volume of combustible mixture which flows through the by-pass, there may be provided therein a regulating valve of any suitable type.

The degree of atomization of the fuel in the combustible mixture and, consequently, the uniformity of distribution of the combustible mixture, when the engine is operating with the throttle closed or only slightly opened, may be increased by heating the combustible mixture as it flows through the by-pass. Means by which the combustible mixture flowing through the by-pass and/or that flowing through the neck 21 may be heated is incorporated in the structure shown in the drawings and will be described directly.

The neck 21 and the adjacent parts of the intake passage 19 are surrounded by a jacket 30. Between the walls of the jacket and the walls of the neck and the header, there is provided a space 31 of which the lower portion is divided into two portions by a wall 32 which extends transversely of the passages 19 and 20. Through the upper wall of the exhaust passage 20, on one side 125 of the wall 32, there extends an opening 33

through which exhaust gases may be admitted into the space 31 and, on the other side of the wall, an opening 34 through which the exhaust gases may be discharged from the 5 space 31. In the wall of the exhaust passage directly beneath the wall 32, there is journaled a shaft 35 on which there is mounted a butterfly type valve 36 which may, by means of an operating arm 37, be shifted so as 10 to cause any desired proportion of the exhaust gases flowing through the passage 20 from the conduit 15 to the opening 17 to pass through the space 31.

It will, of course, be understood that, 15 although I have shown and described my invention as incorporated in a particular type of engine, it may be applied to other engines in which the demand for combustible mixture at the point in the induction system 20 at which the stream of combustible mixture is divided, alternates symmetrically in each of two directions. Specifically, it may be pointed out that the invention is applicable to six cylinder and V-8 engines with 25 crankshafts of which all the throws are located in a single plane and conventional firing order, straight eight engines with single manifolds and crankshafts in which the four throws adjacent one end are located in a 30 single plane and the four throws adjacent the other end are located in a single plane which is located at a right angle to the plane in which the first mentioned throws are located, and straight eight engines with 35 dual manifolds of which one branch supplies the central four cylinders and the other branch the two forward and two rear cylinders and with crankshafts in which the two throws adjacent one end are located in a 40 single plane, the next four succeeding throws are located in a single plane which is located at a right angle to the plane in which the first mentioned throws are located, and the remaining throws are located in a single 45 plane which is located at a right angle to the plane in which the four throws are located.

I claim:

1. In an internal combustion engine of the 50 class described, a plurality of cylinders, a charge forming device, a conduit communicating with the charge forming device, a conduit which communicates intermediate its ends with the first-mentioned conduit, at one 55 end with one or more of the cylinders and at the other end with the other cylinder or cylinders, a valve located on the atmospheric side of the second-mentioned conduit for controlling the passage of combustible mixture from

the charge forming device to the cylinders, a wall which forms a partition within the second-mentioned conduit and which is adapted to divide the stream of combustible mixture which passes the valve into two streams, of 70 which one flows into each of the branches of the second mentioned conduit, and a passage opening into the first-mentioned conduit on the atmospheric side of the valve and having a branch opening into the second-mentioned conduit on each side of the partition. 75

2. In an internal combustion engine of the type described, an intake manifold which includes a T-shaped conduit, a valve in the intermediate branch of the conduit, a partition which is located between the portions of the cross branch of the conduit on the opposite sides of the intermediate branch and which is adapted to divide the stream of combustible mixture which passes the valve into two 80 streams, of which one flows into each of the portions of the cross branch of the conduit, and a passage extending through the walls of the conduit and the partition and communicating at one end with the interior of the conduit on the atmospheric side of the valve and having at its other end branches which open 85 through the partition into the interior of the portions of the cross branch on the opposite sides of the partition. 90

3. In a multi-cylinder internal combustion engine, a charge forming device, an intake manifold in which there are provided a main mixture passage leading from the charge forming device, a branch passage leading from the main mixture passage to a plurality of 100 cylinders, and a second branch passage leading from the main mixture passage to a plurality of cylinders whose suction strokes alternate symmetrically with the suction strokes of the cylinders to which the first branch leads, a valve for controlling the passage of combustible mixture from the charge forming device to the cylinders through the main mixture passage, and a passage communicating 105 with the main mixture passage on both the atmospheric side and the engine side of the valve for conducting combustible mixture around the valve and discharging a portion 110 of it into each of the branch passages alternately.

4. The invention claimed in claim 3 plus means for supplying heat directly to the combustible mixture passing from the charge forming device to the cylinders through the 120 passage for conducting combustible mixture around the valve.

In testimony whereof I affix my signature.
CALEB E. SUMMERS.
